UNITED STATES PATENT OFFICE.

HARRIS T. DUNBAR, OF BUFFALO, NEW YORK.

DUMPING SCOW.

Application filed May 31, 1921. Serial No. 474,053.

To all whom it may concern:

Be it known that J. HARRIS T. DUNBAR, a citizen of the United States, residing in Buffalo, in the county of Erie and State of New York, have invented new and useful Improvements in Dumping Scows, of which the following is a specification.

This invention relates to a dumping scow which is designed to receive a load of material taken from a submarine excavation or elsewhere and discharge the same at any suitable place to which the same has been transported.

It is the object of this invention to provide a scow for this purpose which can be readily loaded, which will properly support its load after receiving the same, which permits of quickly and easily discharging its load either in shallow water as well as deep water without interfering with the movement of the scow, and which is so constructed that the opening of the doors which control the outlets at the lower ends of the wells which receive the load will be aided by the buoyancy of the doors.

In the accompanying drawings:

Figure 1 is a vertical longitudinal section of a dumping scow embodying the preferred form of my invention. Figure 2 is a top plan view of the same, partly in section. Figure 3 is a vertical transverse section, taken on line 3—3, Fig. 1.

Similar characters of reference refer to like parts throughout the several views.

The hull of this scow is preferably hollow and provided with a flat bottom 10, a flat deck 11 and upright side walls connecting the edges of the bottom and deck and having the main central parts 12 thereof arranged lengthwise while the opposite end portions 13 thereof are inclined toward the longitudinal center of the hull so that the opposite ends of the latter are tapered or pointed forwardly, but present vertical edges 14 at the extreme ends of the hull. By this construction of the hull the same, upon striking either of its ends against a hull of similar or other construction, will glance off to one side or the other, excepting when striking another object "dead on," so that the two vessels will pass each other and owing to the vertical edges at the extreme ends, the engagement of these hulls with another one of similar or other construction will not permit one scow to get partly underneath another scow and interfere therewith, as frequently happens in the use of scows in which the ends slope downwardly toward the bottom, which engagement in the last mentioned form of scows very often occurs when a loaded scow encounters a scow which is light and therefore permits the end of the loaded scow to get underneath the inclined end of the unloaded scow and thus interfere with the operation of both.

This hull may be provided with one or more wells extending from the deck to the bottom thereof, two of such wells being shown, for example, in the drawings and each well being designed to form part of a receptacle for carrying the material which is to be transported by the scow. Each of these wells is provided with two longitudinal side walls 15 which are arranged parallel with each other and two transverse walls 16 and 17 which converge downwardly from the top or deck of the hull toward the bottom of the same, the transverse wall 16 being preferably curved while the other transverse wall 17 is preferably straight, as shown in Fig. 1. When two wells are employed in the hull the straight inclined transverse walls of both wells preferably are arranged on the inner sides of the wells or away from the ends of the hull and are joined at their upper ends so as to form an apex 18 whereby any material dropped upon the central part of the scow will be divided by this apex and caused to flow downwardly partly into each one of the wells.

In the case of two wells being arranged next to each other lengthwise in the hull the curved transverse walls 16 are arranged next to the ends 14 of the hull. The lower or outlet end of each well is controlled by a closure which is moved into a position across this outlet so as to form with the well a pocket or receptacle which receives the load to be transported and this closure is movable out of a position across this outlet, so as to permit the load to be discharged from this pocket when the material has been transported to the place where the same is to be discharged. In its preferred form this closure consists of a door which is capable of swinging vertically into and out of its operative position, but at no time extends below the bottom of the hull, this being accomplished by arranging the axis of the door above the well and causing the door, when opening, to swing upwardly with reference to the lower end of the well. In

the preferred construction of this door the same is made hollow and comprises an upper flat wall 19 and a lower curved wall 20 which connects at its opposite ends with the corresponding ends of the front wall 19 and forms therewith a buoyant body, the upwardly swinging movement of which is assisted by the water when the door is free. The bottom 20 of each door is turned about a horizontal axis, which is transverse to the bottom, and one end of the same is preferably arranged comparatively close to the straight inclined wall 17 of the well so as to form a practically tight joint therewith, while its opposite end may be spaced apart or fitted comparatively loose relative to the curved transverse wall 16, as shown in Fig. 1, this being permissible for reasons which will presently appear.

20 Various means may be employed for supporting each door on the hull, those shown in the drawings comprising two arms or hangers 21 which project upwardly from opposite longitudinal ends thereof and provided at their upper ends with laterally projecting trunnions 22 which are arranged horizontally or transversely and journaled in suitable bearings 23 on the adjacent parts of the deck of the hull. The curved lower 25 wall 20 of each door is concentric with the axis of the trunnions 22 and the curved transverse wall 16 of the respective well is also preferably concentric with the trunnions, as shown in Fig. 1, which causes the lower wall of the door to always travel 30 fairly close to the straight transverse wall 17 but remain clear of or spaced apart from the curved wall 16.

The upward movement of each door on 40 that side of the well having the curved transverse wall 16 is limited by a stop device while the scow is being loaded and while the load is being transported but this stop device may be shifted to permit the door to continue its upward movement on 45 that side of the well having the curved wall 16 when it is desired to uncover or open the lower end of the well and permit the load to be discharged therefrom by gravity. This stop device may be variously constructed, but in its preferred form, the same is constructed in the form of a toggle which projects into the path of the door and prevents the same from effecting its opening 50 movement, but can be easily actuated for releasing the door so that the door can be opened automatically by the combined effect of the weight of material on the door and the buoyant effect of the water on the door. In its preferred form this stop device 55 comprises an outer or rear toggle link 24 which is pivoted on the deck of the hull adjacent to the central part of the curved transverse wall 16 thereof, so that the same 60 is capable of swinging in a vertical plane,

and an outer or front toggle link 25 which is pivotally connected with the inner link 24 so as to be capable of swinging in a vertical plane relatively thereto. When the scow is emptied, each of the doors is moved 70 by gravity into a position in which it closes the lower or outlet end of its well in which position the upper wall 19 of the door is horizontal, or substantially so, as shown by full lines in Fig. 1. When loading this scow 75 the material is dropped into the wells so that the greater part of the same rests upon the horizontal wall 19 of each door and the adjacent straight inclined wall 17 of the respective well, while a comparatively small 80 part of the load is arranged on that part of the lower wall 19 adjacent to the curved wall 16, as shown by dotted lines in Fig. 1, thereby causing the weight of the material 85 in each well to turn each door, so that that end thereof next to the inclined wall 17 would be lowest and that end next to the curved wall 16 will be elevated, the movement in this direction being, however, arrested before the well is uncovered at its 90 lower end by engagement of the elevated end of the door with the front end of the outer toggle link which at this time is shifted so as to project into the path of the door. The two toggle links are held at this time 95 in a position in which they are practically rigid by engagement of the inner toggle link with the adjacent part of the curved transverse wall 16 of the respective well, so that the point of engagement between the door 100 and the outer toggle link and the pivotal connections between the inner toggle link and the hull and outer toggle link are on a dead center and remain rigid under the thrust exerted against the same by the door 105 which tends to move forwardly at the respective end by the preponderating pressure of the load bearing against the opposite end thereof.

When it is desired to dump the material 110 from one of the wells the attendant disengages the toggle stop device from the respective door and swings the same vertically out of the path thereof and against the deck of the hull. When this is done, the door is 115 immediately turned into an opened position so that the same uncovers the lower or outlet end of the well, this opening movement of the door being automatic and effected by the preponderating weight of the material 120 resting upon the upper floor 19 thereof between the axis of the door and the straight transverse wall 17 of the well, which movement is aided by the buoyancy of the door, due to its hollow construction. As the door 125 rises on that side next to the curved wall 16 the upper wall 19 of the door assumes a gradually increasing inclination while at the same time the material slides down the inclined transverse wall 17, whereby the entire 130

load is discharged from the well through the lower end or outlet thereof. As soon as the material has slid off from the door the same again returns by gravity into its lower position in which it extends across the outlet of the well, and then the operator again shifts the locking device from the top of the deck into a position in which it stands in the path of that edge of the door next to the curved wall 16 ready to arrest the upward movement thereof and keep the door in its closed position, when a load of material is deposited in the well.

In order to permit the load to discharge promptly from the well and the door to clear itself effectively of the material deposited upon the upper wall 19 thereof, the transverse edge 26 of the well at the lower end of the straight wall 17 is arranged farther from a vertical plane extending through the axis of the door and the transverse edge 27 of the well at the lower end of the curved wall 16, as shown in Fig. 1. As soon as that end of the floor next to the straight wall 17 passes beyond the lower edge 26 thereof the material immediately begins to discharge from the well, which discharge is gradually accelerated as the door continues to swing vertically in the same direction. In order to still further facilitate the discharge of the material from the well and avoid any clogging action, that part of the outlet of the well below the transverse edge 26 is undercut, as shown at 28, whereby any material after passing below the edge 26 will be immediately fully liberated and permitted to drop out of the well without any restriction.

Owing to the fact that the door of the well of this scow at no time passes below the bottom of the hull during the operation of unloading the scow, it is possible to unload this scow in comparatively shallow water without liability of the scow becoming foul of the material which is being discharged, this freedom of the scow from the load being further aided by the fact that the moment the scow begins to unload it becomes lighter and gradually recedes from the discharge load which may be resting on the ground as the discharging operation proceeds. This form of unloading device for a scow is therefore highly advantageous over a scow in which the doors of the wells or pockets swing downwardly from the bottom of the scow and thus become fouled with the load and interfere with the manipulation of the scow which renders it difficult, if not impractical, to dump material from the scow in comparatively shallow water.

In order to protect the bearings on the deck which support the pivots of the doors, two coamings are arranged lengthwise upon the deck along opposite sides of the wells so as to enclose the inner parts of the bearings of the doors, thereby preventing the bucket

of the dredging apparatus, as the same swings over the scow, from injuring these bearings. As shown in the drawings, the several walls or parts of the hull forming the shell of the same and the main parts of the doors are constructed of sheet metal, but it is to be understood that these parts may be constructed of other materials, if desired.

As a whole, this dumping scow is comparatively simple in construction, considering the function it is designed to perform and the same can also be produced at comparatively low cost inasmuch as it has no complicated parts which are liable to get out of order under rough usage to which scows of this character are usually subjected.

I claim as my invention:

1. A dumping scow comprising a hull provided with a well extending from the top to the bottom thereof, and a vertically swinging door pivoted on said hull and adapted to close and open the lower end of said well said door having a flat upper side while its underside is curved concentrically with its axis.

2. A dumping scow comprising a hull provided with a well extending from the top to the bottom thereof, and a door adapted to swing in a vertical plane into and out of a position across the lower end of said well and having arms at its opposite ends which are pivotally mounted at their upper ends on said hull.

3. A dumping scow comprising a hull provided with a well extending from the top to the bottom thereof, bearings arranged on the upper side of said hull on opposite sides of the well, and a door adapted to swing in a vertical plane into and out of a position across the lower end of said well and provided at its opposite ends with upwardly projecting arms having trunnions at their upper ends which are journaled in said bearings.

4. A dumping scow comprising a hull provided with a well extending from the top to the bottom thereof, and a door adapted to swing in a vertical plane into and out of a position across the lower end of said well and having arms at its opposite ends which are pivotally mounted at their upper ends on said hull, said door having a flat upper side while its underside is curved concentrically with its axis.

5. A dumping scow comprising a hull having a well extending from the top to the bottom thereof and two opposing sides of the well being upright and parallel and two other sides thereof converging downwardly, and a door pivotally mounted on the hull so as to be capable of swinging into and out of a position across the lower end of said well said door having a flat upper side while its underside is curved concentrically with its axis.

6. A dumping scow comprising a hull having a well extending from the top to the bottom thereof and two opposing sides of the well being upright and parallel and two other sides thereof converging downwardly, and a door pivotally mounted on the hull so as to be capable of swinging parallel with the upright sides of the well into and out of a position across the lower end of said well 10 said door having a flat upper side while its underside is curved concentrically with its axis.

7. A dumping scow comprising a hull having a well extending from the top to the bottom thereof and two opposing sides of the same being upright and parallel and the other two sides thereof converging downwardly, one of the converging pair of sides being straight and the other curved, and a door pivotally mounted on the hull to swing parallel with said upright sides and having a flat top and a curved bottom which is concentric with the axis of the door and the curved side of the well.

8. A dumping scow comprising a hull having a well extending from the top to the bottom thereof and two opposing sides of the same being upright and parallel and the other two sides thereof converging downwardly, one of the converging pair of sides being straight and the other curved, a door pivotally mounted on the hull to swing parallel with said upright sides and having a flat top and a curved bottom which is concentric with the axis of the door and the curved side of the well, and a movable stop mounted on the hull and adapted to be engaged by that part of said door adjacent to the curved side of said well.

9. A dumping scow comprising a hull having a well extending from the top to the bottom thereof and two opposing sides of the same being upright and parallel and the other two sides thereof converging downwardly, one of the converging pair of sides being straight and the other curved, a door pivotally mounted on the hull to swing par-

allel with said upright sides and having a flat top and a curved bottom which is concentric with the axis of the door and the 50 curved side of the well, and a movable stop mounted on the hull and adapted to be engaged by that part of said door adjacent to the curved side of said well, and comprising an inner toggle link pivoted on the hull to 55 swing vertically and an outer toggle link pivoted on said inner link to swing vertically and adapted to be engaged by the adjacent part of the door, the pivotally connected ends of said inner and outer links being 60 adapted to engage a stationary part of said hull.

10. A dumping scow comprising a hull having two wells extending from the top to the bottom thereof and separated from each other by a partition which slopes toward opposite ends of the hull and forms the inner transverse sides of said wells, and doors for controlling the lower ends of said wells and pivoted on said hull to swing lengthwise of 70 the latter and about horizontal axes.

11. A dumping scow comprising a hull having a well extending from the top to the bottom thereof, and a door swinging on said hull about a horizontal transverse axis and adapted to control the lower end of said well, one of the transverse edges of the lower end of said well being nearer a vertical plane 75 extending transversely through the axis of said door than the other transverse edge of 80 the lower end of the well.

12. A dumping scow comprising a hull having a well extending from the top to the bottom thereof, and a door swinging on said hull about a horizontal transverse axis and adapted to control the lower end of said well, one of the transverse edges of the lower end of said well being nearer a vertical plane 85 extending transversely through the axis of said door than the other transverse edge of 90 the lower end of the well and that transverse edge at the lower end of the well farthest from said plane being undercut.

HARRIS T. DUNBAR.
